UNITED STATES PATENT OFFICE.

THOMAS MATTHEWS, OF BROOKLYN, NEW YORK.

BUOY.

977,959.

Specification of Letters Patent.

Patented Dec. 6, 1910.

Application filed December 18, 1908. Serial No. 533,871.

To all whom it may concern:

Be it known that I, THOMAS MATTHEWS, a citizen of the United States, residing at Brooklyn, in the county of Kings and State 5 of New York, have invented new and useful Improvements in Buoys, of which the following is a specification.

This invention relates to buoys, the object in view being to provide a buoy especially 10 designed for the purpose of marking the place where a vessel sinks and also containing important data such as the items usually recorded in the log-book together with any notes, communications or valuable property 15 of passengers on the vessel.

A further object of the invention is to provide a buoy of such construction as to enable articles of the class above referred to to be introduced into the interior of the buoy 20 while preventing their extraction therefrom without showing that the buoy has been opened for the purpose of obtaining access to the contents thereof.

With the above and other objects in view, 25 the nature of which will more fully appear as the description proceeds, the invention consists in the novel construction, combination and arrangement of parts as herein fully described, illustrated and claimed.

30 In the accompanying drawings:—Figure 1 is a vertical diametrical section through a buoy constructed in accordance with the present invention. Fig. 2 is a similar view on an enlarged scale taken through the head 35 of the buoy. Fig. 3 is a plan view of the upper edge of the main body of the buoy with the upper cap section detached.

Referring to the drawing, 1 designates the body of the buoy, the upper portion of 40 which is of frusto-conical shape while the lower portion 2 thereof is substantially hemispherical and contains within it a molded ballast block 3 which is preferably secured in place by means of an eye bolt 4, the 45 eye 5 of which is arranged exteriorly of and beneath the bottom of the buoy.

Within the body of the buoy is arranged at a suitable elevation a deck 6 adapted to support the various articles placed therein 50 an entrance to which may be effected by means of a port-hole 7 in one side thereof.

By reference to Fig. 2 it will be observed that the body 1 is provided at its upper edge with a gasket flange 8 which is rabbeted as 55 shown at 9 to receive an annular gasket 10

preferably round in cross section. The upper end of the body 1 is closed by means of a hemispherical cap section 11 which is provided at its lower edge with a gasket flange 12 having a half round groove 13 to receive the projecting portion of the gasket 10, referred to. The cap 11 is hinged to the main body 1 of the buoy as shown at 14 and is provided at its opposite side with a spring catch 15 adapted to snap into engagement with the keeper 16 on the body 1 when the cap is closed, thus preventing the accidental opening of the cap section.

17 designates a cap closing spring, one end of which is secured to the body 1 at the fixed point 18, while the other end of the spring is secured to the inner end of an eye bolt 19, the eye 20 of which is arranged exteriorly of and above the cap section 11. The spring 17 acts to snap the cover section closed after 75 it has been lifted for the purpose of introducing any articles therein.

On one side, the buoy is provided with a suitable number of clamps 21 adapted to receive the staff 22 of a signal 23 such as a 80 flag which designates the buoy as marking a sunken vessel. Connected to the eye 5 at the bottom of the buoy is a line 24 preferably consisting of a copper wire of suitable length which is wound upon a reel 25 and 85 secured at one end to said reel so as not to become detached therefrom. This reel is adapted to be mounted upon the deck of a vessel and anchored in any way to the deck 90 of the vessel so that in case the vessel sinks the buoy will float upon the surface of the water and will cause an unreeling of the line 24 until the vessel reaches the bed of the body of water.

95 The buoy is adapted to contain the log notes of the officer of the watch containing the statement of the latitude and longitude, the course of the vessel and general conditions and is also adapted to contain notes or communications, wills and the like as well as valuables of passengers on the vessel, so that such material may be picked up by a vessel sighting the buoy.

I claim:—

A buoy for the purpose specified comprising a hollow floating body embodying a hemispherical bottom portion and a correspondingly shaped ballasting lining in said base, an elevated deck within the body, a 110

reel having a line wound thereon with one end connected to the reel and the other end connected to the buoy body and a hollow hemispherical cap section hinged to the main body of the buoy, a spring for closing said cap section, a spring catch for holding the cap section closed and an annular gasket of cylindrical shape in cross section seated in semi-cylindrical grooves in the abutting

edges of the main body and cap section of the 10 buoy, substantially as described.

In testimony whereof I affix my signature in presence of two witnesses.

THOMAS MATTHEWS.

Witnesses:

THOMAS J. DRISCOLL,
A. C. McAULIFFE.
